UNITED STATES PATENT OFFICE.

ALFRED L. ATHERTON, OF PITTSBURGH, PENNSYLVANIA, ASSIGNOR TO WESTINGHOUSE ELECTRIC & MANUFACTURING COMPANY, A CORPORATION OF PENNSYLVANIA.

LIGHTNING ARRESTER.

Application filed September 19, 1922. Serial No. 589,087.

My invention relates to lightning arresters, more especially to the multiple-gap type commonly employed in alternating-current circuits.

- 5 It is among the objects of this invention to provide an arrester which is of simple compact structure, readily accessible and applicable to alternating-current transmission lines.
- 10 It is a further object of this invention to provide a structure which shall be relatively inexpensive to manufacture in production quantities.

Lightning arresters of the series multi-
15 gap type heretofore employed function upon the principle of obtaining a discharge of abnormal surges from a line to ground through a series of arc gaps having a resistance in series therewith.

20 My present invention is directed to a structure which comprises a relatively large number of such discharge gaps, each having resistance in series therewith, but connected in parallel or shunt groups. The structure
25 is relatively simple and is contained within a compact unit to make it commercially applicable.

In the accompanying drawings constituting a part hereof and in which like reference characters designate like parts,

Fig. 1 is a plan view of a resistor element of a lightning arrester embodying the principles of my invention, and

Fig. 2 is a cross-sectional view of the 35 lightning arrester taken along the lines II—II of Fig. 1.

Referring to the drawing, the arrester may comprise a plurality of metal plates constituting electrodes 30 having insulating 40 spacer rings 31 disposed therebetween. Resistor disks 32, provided with surface coatings 33 or non-arcng conductor material, such as brass, and having a large number of parallel transverse slots or recesses 34, are disposed 45 between adjacent electrodes 30. The dimensions of the electrodes 30 and the spacer rings 31 are such as to provide suitable spaces or gap 35 between the resistor surface coatings 33 and the metal-plate electrodes 30, 50 thus establishing a plurality of individual sparking surfaces 36 in shunt to said metal-plate electrodes. Any number of such constructed layers may be stacked in multiple to provide an arrester of the desired capacity, 55 as in Fig. 2.

The function of these arresters is such that, when the device is connected in a circuit, discharge will be effected, through the individual sparking surfaces 36 and the several serially related sections of the resistors 32, the resistances of which are sufficiently high to limit the current-carrying capacity of each sparking surface 36 to a small value, so that the continued flow of the line current, after an excess-voltage discharge, 60 is effectively prevented, the discharge being distributed over a wide area of low current-density, instead of being concentrated in a single point, as in arresters of the prior art. The relatively large number of gaps 35 70 built up in shunt groups thus increases the discharge capacity to a relatively large degree without raising the current across each gap and without requiring the height of construction heretofore employed in arrestors 75 of the low-equivalent type.

It will be evident from the above description that a lightning arrester built in accordance therewith provides an efficient discharge path for abnormal voltages or 80 surges on power transmission lines, thereby protecting the insulation of electrical devices embodied in such circuits.

A further advantage is that such a device provides a plurality of spark gaps which, 85 owing to the series resistances, are individually of a low current capacity but, as a unit, provide a relatively large current capacity for the size of the structure.

Although I have described a specific embodiment of my invention, it will be obvious to those skilled in the art that various modifications may be made in the details of construction without departing from the principles herein set forth. For instance, 90 any arrangement of resistors to produce a plurality of spark gaps in shunt may be provided in place of the structure herein described, or the devices illustrated may be enclosed within a suitable container or in 95 other ways modified to adapt them to the specific service in which they are to be used.

I claim as my invention:

1. A lightning arrester comprising a pair of electrodes having a gap therebetween, one of said electrodes comprising resistance material having its gap surface divided into a large number of sparking surfaces by means of a large number of slots, the resistances of the several serially related sec- 110

tions of the resistance material being sufficiently high to limit the current-carrying capacity of each of the said sparking surfaces to a small value, so that the total discharge 5 of the arrester is distributed over a plurality of said sparking surfaces instead of being concentrated in a single arc.

2. A lightning arrester comprising a pair 10 of electrodes having a gap therebetween, one of said electrodes comprising resistance material having its gap surface coated with metal and divided into a large number of 15 sparking surfaces by means of a large number of slots, the resistances of the several serially related sections of the resistance material being sufficiently high to limit the current-carrying capacity of each of the said 20 sparking surfaces to a small value, so that the total discharge of the arrester is distributed over a plurality of said sparking

surfaces instead of being concentrated in a single arc.

3. A lightning arrester comprising a group of resistor elements arranged in side-by-side relation to form parallel, substantially distinct current discharge paths, an electrode member spaced from the ends of 25 said resistor elements to constitute a plurality of discharge gaps in series with said parallel paths, the resistance of each path being sufficiently large to restrict the current in each individual path to a relatively small value, and the total number of parallel discharge paths being sufficient to provide a 30 relatively large discharge capacity. 35

In testimony whereof, I have hereunto subscribed my name this 25th day of August 1922.

ALFRED L. ATHERTON.
